FLAME DETECTOR SYSTEM

John F. Van Driel, Irvington, N.J., assignor to Petcar Research Corporation, Washington, D.C., a corporation of New Jersey

Application December 28, 1955, Serial No. 555,932

1 Claim. (Cl. 340—227)

This invention relates, in general, to fire detector systems and, more particularly, to such systems which are operative to provide a signal only when actual flame impinges on the sensing element of the system and ground.

Systems of the particular type to which the invention relates are known and it has been the principal object of the invention to provide a simplified system of this type which is constructed and operative in a new and improved manner to provide an indication of "fire" only upon impingement of actual flame on the sensing element and ground. A further object of this invention has been to provide a fire detector system which will produce a signal when a flame impinges on the sensing element and ground but which will not be operative by irregular intermittent pulses such as rain and the like. Other objects and features of novelty of the invention will be made apparent by the following description and the annexed drawing, in which:

Fig. 1 is a block diagram of a fire detector system according to the invention in which the sensing element is connected to a source of direct current, and

Fig. 2 is a block diagram of a fire detector system according to the invention in which the sensing element is connected to a source of alternating current.

It has heretofore been observed (see Industrial and Engineering Chemistry, vol. 20, No. 10, page 1012, October, 1928) that the upper portion of the luminous zone of a flame rises to a maximum height at a regular frequency which may be between three and thirty times per second but which is most prevalently ten times per second, and that the lower portion of the luminous zone of the flame has a continuous existence but periodically, at the same frequency as the upper part, gives off another flame which rises above the lower portion of the flame during its short period of existence. It has been found that the rate of this flickering of any flame is not greatly affected by change in conditions to which the flame is subject and will remain fairly constant within the limits set forth above. In the present invention I have utilized this characteristic of a flame to "flicker" at a frequency within well-defined limits to provide a system which produces an indication whenever a flame impinges on the sensing element forming part of the detector system.

According to the invention a bare sensing element, which is insulated from ground, is connected to a source of direct or alternating current. Impingement of a flame upon the sensing element causes current to flow between the sensing element and ground. The magnitude of the current is determined by the size of the flame and by the degree of contact between the flame and the sensing element and between the flame and ground. Due to the flicker of the flame none of these quantities remains constant. Therefore, the magnitude of the current will vary at the same frequency as the flicker of the flame. If the voltage source presents a reasonably high impedance to the flow of current at these

2

frequencies, a voltage will be produced between the sensing element and ground that will have the same frequency as the frequency of the flicker of the flame. The voltages so produced are amplified and supplied to an amplitude discriminator circuit which produces a voltage pulse when the amplified output exceeds a predetermined level, thus eliminating the effect of inherent circuit noise within the system, hum and other such extraneous noises. An integrating circuit is connected to the output of the discriminator circuit to integrate the discriminator output. The integrator causes the detector system to be responsive only to signals having a definite minimum duration and to not respond to signals of a shorter duration such as those that might be caused by rain, static electricity discharges and other similar signal sources. The output of the integrator is amplified and supplied to a relay which operates an indicating device.

A flame detector system according to the invention is shown in block diagram in Fig. 1 and comprises a sensing element or electrode 2 which may be any bare electrode such as a wire, screen or the like, and which is insulated from ground by insulators 4. A source of direct current 6 is connected between ground at 8 and the input end of electrode 2 through a band reject filter 24. The band reject filter serves the dual purpose of insuring that the voltage source presents a high impedance to the signal produced by the flame and of preventing any possibility of operation of the detector by signals from any other source which might be transmitted through the voltage source. Normally, no current flows in the electrode 2 as it is not grounded, but when a flame impinges on it a current will flow because of the grounding of the flame and this current will pulsate at the frequency of flicker of the flame.

Voltage pulses produced in the electrode must be amplified to provide sufficient power to actuate a signal device. The fluctuating voltage produced in the sensing element upon impingement of a flame on both the element and ground is accordingly supplied to a band pass amplifier 10, through a band pass filter 26, both of which are responsive to signals in the 3 to 30 c.p.s. range. The band pass filter, 26, is so constructed that it will pass frequencies in the 3 to 30 c.p.s. range and will reject but not short out all other frequencies. To reduce the possibility of hum and circuit noise producing a signal, an amplitude discriminator 12 is connected to the output of the amplifier 10. This amplitude discriminator may be a circuit known as a "Schmitt Trigger circuit" which may be made to operate so that when an A.C. signal that is above a certain adjustable minimum is applied to the input, the output is essentially a square wave of the same frequency as the input. The minimum is adjusted so that circuit noise, hum and other similar noises produced in the detector will not produce an output but the signals produced by a flame impinging on the sensing element and ground will produce an output. Thus the effects of inherent circuit noise and low-level spurious voltages are minimized.

60 The output waveform from the amplitude discriminator is supplied to an integrator 14 which has circuitry such that it will not produce an output of sufficient amplitude to cause operation of the relay circuit unless its input signal is of a certain minimum duration. This produces a delay in operation of the relay circuit such that large sporadic signals such as those produced by rain, static electricity discharges and the like will not cause operation of the relay circuit. The delay is, however, short enough for the reaction of the detector to flame to be considered instantaneous. In this manner the effect of low frequency spurious responses are minimized.

The combination of the Schmitt trigger and integrator circuits produces a voltage which is essentially independent of the amplitude and frequency of the signal into the Schmitt trigger. The trigger circuit produces a constant amplitude square wave whose frequency is the same as the frequency at its input. When this square wave is integrated by the integrator, its output is essentially the same for any frequency.

The output of the integrator is coupled to a relay control tube 16 which operates a relay 18. As the voltage output of the integrator is a relatively slowly rising voltage whose amplitude is determined by the duration of the signal to it, the relay is adjusted to operate at a pre-determined voltage which is above that caused by spurious signals and below that caused by flame. Operation of the relay connects an indicating device 20, such as a lamp, to a source of electrical energy 22 to energize the indicating device.

In the operation of the detector system according to this invention a low voltage direct current is constantly available at the sensing element 2 but normally does not flow therein because of the insulation of the sensing element from ground. When a flame impinges on the sensing element and ground the pulsating or flickering character of the flame distorts the direct current voltage between the sensing element and ground causing pulses to be produced at the frequency of the flicker of the flame. These pulses are amplified and passed to an amplitude discriminator if their frequency lies within the 3 to 30 c.p.s. band pass width of the amplifier. The amplitude discriminator eliminates all pulses below a predetermined voltage and supplies those of greater voltage to an integrator which eliminates all signals not having a minimum duration and which are of a frequency lying within the aforesaid range, thus eliminating signals due to extraneous causes such as rain. The output of the integrator is supplied to a relay control tube which operates a relay when energized, to cause operating of an indicator, thus indicating the impingement of flame on the sensing element and ground.

In Fig. 2 of the drawing there is disclosed another embodiment of the invention in which the sensing element 2 is connected to a source of alternating voltage 30 through a band reject filter 46 instead of the source of direct current 6 of the embodiment disclosed in Fig. 1. The band reject filter, as before, will present a high impedance to the signal produced by flame and will prevent operation by signals from the source. The frequency of this source is such that it will not be in the 3 to 30 c.p.s. range and one to which the band pass amplifier will not respond. The sensing element is insulated from ground by insulators 4 and therefore no current normally flows in the element. The output end of the sensing element is connected through a band

5 pass filter 48 to a band pass amplifier 32, the output of which is connected through amplitude discriminator 34, integrator 36 and relay control circuit 38 to relay 40 which controls the connection of indicator 42 to a source of electric energy 44. In all respects, the operation of the system disclosed in Fig. 2 is the same as that of the system disclosed in Fig. 1. Normally, no current flows from the sensing element 2 to ground but when a grounded flame impinges on this element an alternating current will flow between the wire and ground at the frequency of flicker of the flame. The distorted alternating current will appear at the input to the band pass filter 48 which will pass only the frequencies of flicker for the band pass amplifier 32 to amplify and will reject but not short out all other frequencies. The function and operation of the parts of the system following amplifier 32 are exactly the same as described hereinbefore in connection with the system disclosed in Fig. 1 and no further description thereof is believed to be required.

10 20 While I have described and illustrated certain forms which my invention may take it will be apparent to those skilled in the art that other embodiments, as well as modifications of those disclosed, may be made and practised without departing in any way from the spirit or scope of the invention, for the limits of which reference must be made to the appended claim.

15 25 30 35 40 45 What is claimed is:

A flame detector system comprising a sensing element consisting of a bare electrode insulated from ground, a source of electric energy connected between said electrode and ground, means for amplifying voltage pulses produced between said electrode and ground by impingement of a flame simultaneously on said electrode and ground, amplitude discriminating means admitting amplified signal voltages appearing between said electrode and ground exceeding a pre-determined amplitude and rejecting other amplified noise voltages below such pre-determined amplitude, means for integrating the square wave output of the amplitude discriminator over a unit of time, indicating means, and means for operating the indicating means when the output of the integrator reaches a pre-determined voltage.
